UNITED STATES PATENT OFFICE.

EDWARD J. HOFF, OF BERKELEY, CALIFORNIA.

AUTOMATIC WEIR FOR REGULATING THE FLOW OF WATER.

1,263,768.

Specification of Letters Patent.

Patented Apr. 23, 1918.

Application filed March 16, 1917. Serial No. 155,357.

(DEDICATED TO THE PUBLIC.)

To all whom it may concern:

Be it known that I, EDWARD J. HOFF, a citizen of the United States, and an employee of the Department of Agriculture of the United States of America, residing at Berkeley, in the State of California, (whose post-office address is Budd Hall, Univ. of Cal., Berkeley, Cal.,) have invented a new and useful Automatic Weir for Regulating the Flow of Water.

This application is made under the act of March 3, 1883, chapter 143 (22 Stat., 625), and the invention herein described and claimed may be used by the Government of the United States or any of its officers or employees in the prosecution of work for the Government, or any person in the United States, without payment to me of any royalty thereon.

20 The object of my invention is to provide an apparatus which is simple in construction and operation and which is specially adapted for accurately regulating the flow of irrigation water, thereby providing means whereby the farmer may be enabled properly to apportion his water supply to his field.

30 The objects, characteristic features and scope of my invention will be more readily understood from the following description taken in connection with the accompanying drawings, wherein:

Figure 1 is a perspective view of my device;

35 Fig. 2 is a side elevation of the same looking down stream with curtain on;

Fig. 3 is a vertical sectional view thereof, and

Fig. 4 is a plan view of the device.

40 Referring to the drawings, A represents the framework of the rectangular weir which may be constructed of any suitable material, preferably of wood. A partition, B, extends from one side of the interior of the framework, A, to the other, having an opening, C, in its upper portion, through which the water flows upon passing from the weir; small rods, e, are secured in the partition, B, at its lower edge and extending upwardly through the opening, C, and are secured at the top to a horizontal, preferably metal, bar. In each side of the framework, A, and adjacent to the junction of said framework, A, and the partition, B,

are slots, D, arranged so as to communicate with the vertical boxes, E, fastened to the sides of the said framework, A, said boxes, E, having removable tops, F. Arranged in the boxes, E, are floats, G, through which pass rods, H, said rods, H, having at their lower ends hooks, N, to engage and movably support the ends of the roller, I, said roller, I, extending through the slots, D, and crosswise the entire width of the interior of said framework, and the said rods, H, being threaded at their upper ends to engage screw nuts, O, by means of which the distance between the top of the curtain and the plane of the floats can be increased or diminished.

Secured to the partition, B, beneath the opening, C, is a flexible curtain, J, the free end of which is thrown over the roller, I, which is itself a float and ballasted to hold the free end below the water surface. The ballast can be adjusted so that friction at the roller end bearings is reduced to a minimum. The least change in the water level will, by raising or lowering the floats, G, produce a like change in the position of the roller, I.

Adjusted to the said weir in any suitable manner near the entrance thereof, is a rod grating, K, pivotally attached at its upper end to the sides of the framework and extending obliquely downward into the weir so that its lower end will pass slightly beneath the surface of the water, which serves the purpose of preventing débris from entering the weir and clogging it.

In practising my invention, it is merely necessary to install the weir, when constructed in the manner hereinbefore described, in any irrigation ditch. The water from said source enters the weir, and, upon rising therein to a height where it reaches the bottom of the slots, D, flows through said slots into the boxes, E, coming in contact with the floats, G. As the water fills the boxes, E, it carries the floats, G, upwardly with its rise. The floats ascending with the rise of the water automatically raise, by means of the hooks N, the roller, I, which in turn raises the curtain, J, all as hereinbefore described. The floats, G, hooks, N, and roller, I, are so adjusted by means of the screw nuts, O, that the curtain, J, is maintained at a fixed level beneath the surface of the water flow. In this way, a definite and specific quantity of

water is allowed to be discharged through the opening, C, irrespective of the volume of water flowing into the weir.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described my invention, I claim:

A weir of the character described, comprising a rectangular framework provided with a partition extending crosswise its in-

terior and having boxes on the exterior of the sides thereof, slots in the sides of said framework for forming a passageway to said boxes and an opening in the upper portion of said partition, floats arranged in said boxes for supporting a roller extending through said slots crosswise the interior of the weir and a flexible curtain having one end secured to said partition and its free end overlapping said roller for automatically regulating the flow of water, substantially as specified.

In testimony whereof, I affix my signature in the presence of two subscribing witnesses.

EDWARD J. HOFF.

Witnesses:

W. B. MURRAY,
WELLS A. HUTCHINS.
